LOCK

Alfred E. Buerosse, Wauwatosa, Wis.

Application October 1, 1932. Serial No. 635,717

22 Claims. (Cl. 70—54)

This invention relates to locks and refers more particularly to permutation locks for securing doors or closures and particularly the doors of safes and the like closed.

5. It is a general object of this invention to provide a lock of the character described which is actuated by push buttons.

Another object of this invention is to provide a lock capable of actuation by push buttons to 10 avoid objectionable projections beyond the face of the door or panel mounting the lock.

A further purpose of this invention is to provide a lock of the character described, the unlocking of which requires the successive depression of all of a series of push buttons.

Another object of this invention resides in the provision of means whereby the mechanism may be secured in a partially locked condition to facilitate locking and unlocking thereof during 20 the day time or when frequent opening and closing is required.

Another object of this invention resides in the provision of a lock mechanism of the character described embodying a locking bolt adapted to 25 be retracted against the force of a spring, by the successive depression of a series of buttons operating on said locking bolt through the medium of levers.

And a further object of this invention resides 30 in the provision of a permutation lock mechanism of the character described which is so constructed as to readily enable changing or resetting of its combination.

With the above and other objects in view 35 which will appear as the description proceeds, the invention resides in the novel construction, combination and arrangement of parts substantially as hereinafter described and more particularly defined by the appended claims, it being understood that such changes in the precise embodiment of the herein disclosed invention 40 may be made as come within the scope of the claims.

In the accompanying drawings, one complete 45 example of the physical embodiment of this invention is illustrated constructed according to the best mode so far devised for the practical application of the principles thereof, and in which:

50. Figure 1 is a front elevation of a conventional safe provided with the lock mechanism of this invention and illustrating the arrangement of the actuating buttons;

Figure 2 is a rear view of the door of the 55 safe with parts broken away and in section and

illustrating particularly the disposition of the lock mechanism thereon;

Figure 3 is a sectional view taken through Figure 2 on the plane of the line 3—3;

Figure 4 is a sectional view taken through 60 Figure 3 on the plane of the line 4—4;

Figure 5 is a sectional view taken through Figure 4 on the plane of the line 5—5;

Figure 6 is a cross sectional view taken through 65 Figure 4 on the plane of the line 6—6;

Figure 7 is a detail perspective view of the bolt moving plate and the latch for holding the same in an intermediate position; and

Figure 8 is a detail sectional view taken through Figure 2 on the plane of the line 8—8. 70

Referring now more particularly to the accompanying drawings, in which like numerals designate like parts throughout the several views, the numeral 1 indicates a safe of conventional construction having a door 2 hingedly mounted 75 to swing open and closed.

To avoid objectionable projections beyond the front face of the safe, the hinges 3 of the door are preferably entirely concealed and disposed within the structure of the door and the wall of the safe to which it is hinged. Concealing the 80 hinges in this manner substantially reduces the effective depth of the safe and thus facilitates its passage through doors and narrow corridors, but this advantage was heretofore counter-acted 85 by the dial and knob of the conventional lock mechanism employed to secure the door closed.

In the present instance, the lock mechanism, indicated generally by the numeral 4, is positioned behind the front wall or face plate 5 of the door as is customary, and while its actuating means which comprises a small rotatable knob 6 and a plurality of buttons 7, projects beyond the face of the wall 5, the distance the knob 6 and buttons 7 project is small as compared to the conventional dial and knob. 95

The lock mechanism comprises a main bolt 8: 100 slideable through an aperture 9 in one wall 10 of an enclosure 11 mounted on the inner face of the door. The lock mechanism is disposed entirely within this enclosure, and as a protection against fire, the entire enclosure is packed with asbestos. For the sake of clarity, this packing of asbestos has not been illustrated. 105

The bolt 8 is mounted on an arm 12 extending upwardly from a plate 13 slidably mounted in fixed guides 14 and 15 and yieldably urged to project the bolt outwardly of the aperture 9 into locking position, by an expansive spring 16. Obviously when the door is closed and the bolt 8 is 110

projected to its locking position by the spring, the end thereof enters a keeper opening (not shown) formed in the adjacent wall of the safe.

The guides 14 and 15 comprise a plurality of 5 U-shaped supporting brackets 17 secured to a base plate 18, which in turn is fixed to the inner face of the wall 5, and flanged plates 19 attached to the arms of the U-shaped brackets 17 by screws 20. The flanges 21 of the plates are spaced from 10 the ends of the bracket arms a distance to slidably receive the plate 13.

The plate 13 is provided with a plurality of 15 holes 22 arranged in two sets and in three rows. In certain of these holes stop pins 23 are positioned, the location of the pins determining the combination of the lock mechanism as will be hereinafter more fully described.

These pins 23 may be of any suitable construction, but in the present instance have heads 24 20 adapted to abut the inner face of the plate 13 and project therefrom to form stops. Cotter pins 25 passed through the inner ends of the pins serve to readily detachably secure the pins in their respective apertures.

25 Between the plate 13 and the wall 5 of the door directly behind the push buttons 7 are two sets of pivoted levers 26. These levers are disposed in planes coinciding with the three longitudinal axes on which the pins 23 are positioned, and are so mounted as to engage the heads of the pins upon actuation thereof to move the plate 13 rearwardly against the action of its spring 16. The sequence of operation of the pivoted levers 26 will be later described.

30 35 Each lever 26 is substantially a bell crank having arms 27 and 28 connected by a web 29. The levers are mounted for pivotal movement by shafts 30 having their opposite ends fixed in the arms of the brackets 17 and are maintained properly spaced on the shafts 30 by spacers 31. Springs 32 carried by the levers and having their free ends engaging rods 33 parallel to the shafts 30, serve to yieldingly urge the levers to their 40 normal inoperative positions at which they are disengaged from their respective stop pins.

45 50 The normal inoperative positions of the levers 26 are defined by the engagement of their arms 27 with the inner ends of their respective actuator buttons. These buttons are slidably mounted in apertures extending through the wall 5, the base plate 18, and reinforcing bars 34 secured to the inner face of the base plate 18. Pins 34' carried by the buttons limit their outward projection.

55 60 From the description thus far, it is evident that the retraction of the bolt out of locking position is effected by the pressing of the buttons 7 in a sequence determined by the location of the stop pins 23. The bolt is held in its retracted position by the projection of a lever 35 into a notch or recess 36 formed in the plate 13, the plate of the guide 15 being cut away to permit such engagement.

65 70 This lever 35 is pivotally mounted, as at 37, from a supporting bracket 38 carried by the base plate 18 and is actuated to and from operative position by rotation of the knob 6 through the medium of a cam 39 eccentrically mounted on a shaft 40. The shaft 40 provides the stem for the actuator knob 6 and is suitably journaled in the wall 5 of the door and in the supporting bracket 38. The cam 39 is secured to the inner end of the shaft as illustrated in Figures 3 and 8, and operates in a slot 41 formed in the lever arm 35. The slot 41 is of such length and is so positioned

75 with respect to the shaft 40 as to limit the rotation thereof to 180°.

80 Obviously, the toe of the lever 35 cannot be engaged in the notch or recess 36 unless the plate 13 and the main bolt 8 connected therewith is fully retracted.

85 The lever 35, besides affording means to secure the main bolt in its retracted position, also directly actuates an auxiliary bolt 42 to and from operative position. The auxiliary bolt 42 is secured to one end of a bar 43 which is slidably mounted by means of a supporting arm 44 received in an elongated slot 45 formed in the bar. An operative connection is afforded between the lever 35 and the bar 43 by a pin 46 received between the arms of the bifurcated end 47 of the lever 35.

90 Consequently when the knob 6 is turned to throw the lever 35 into its operative position projected into the recess 36, the auxiliary bolt 42 is retracted, but retraction is impossible until the main bolt has been completely withdrawn which requires depression of all of the buttons 7 in the proper sequence. Double security is thus afforded against unauthorized unlocking of the 100 mechanism.

95 In some instances where the safe is frequently opened and closed as during the day time in a busy commercial establishment, it is inconvenient to go through the entire combination every 105 time the door is to be opened. For this reason a latch 48 is provided to releasably hold the main bolt in a partially retracted position from which complete retraction can be quickly effected by actuating only some of the buttons 7. This latch 110 consists of a substantially U-shaped element having a latching finger 49 at one side of its central web 50 and an actuating finger 51 at the opposite side thereof with its arms 52 drilled to receive a shaft 53. The shaft 53 is slidable in 115 aligned apertures formed in the plates 19 and is yieldingly urged upwardly by a spring 54 coiled about its upper end and confined between a stop washer 55 carried by the shaft and the adjacent plate 19. The movement of the shaft 120 by the spring 54 is limited by a cross pin 56 fixed in the opposite end of the shaft and engageable with the other plate 19. A stop pin 57 passed through the shaft 53 and engaging the lowermost arm 52 of the latch serves to hold it 125 in a position at which its latching finger and actuating finger are aligned with the center row of stop pins 23.

130 135 From Figures 4 and 7, it is seen that as the plate 13 is retracted against the actuation of its spring 16 by the proper manipulation of the buttons 7, the actuating finger 51 will be lifted by one of the pins 23 to swing the latch 48 about the axis of the shaft 53 and position the latching finger 49 in the path of a stop 58 carried by the plate. The stop 58 as a matter of convenience, may be identical with the pins 23.

140 145 The stop 58 is so located with respect to the latching finger 49 that, if the plate 13 is released from its fully retracted position, by withdrawal of the lever 35 from engagement with the plate, it will arrest the motion of the plate at an intermediate position from which it may be returned to its fully retracted position by the actuation of only two buttons. In this intermediate position, the main bolt is projected only a portion of its total travel, but the auxiliary bolt 42 is projected its entire distance. Release of the main bolt from the intermediate position at which it is held by latch 48, for the completion 150

of its locking movement is effected by shifting the latch 48 downwardly. Such downward shifting of the latch is accomplished by the depression of an additional button 59.

5 The button 59 is slidably projected through aligned openings in the door and base plate 18 and projects through an opening in a mounting bracket 60 riveted to the base plate (see Figure 6). An upset head 61 on the inner end of the button precludes its outward displacement. The inner end of the button is engageable with a segment 62 pivotally mounted from the bracket 60, as at 63, and serving in the capacity of a bell crank lever with a portion thereof engaging the lower arm 52 of the latch. Hence, depression of the button 59 swings the segment 62 about its mounting 63 and pushes the entire latch downwardly out of alignment with the center row of stop pins 23, to free the plate 13 and the main bolt connected thereto for the completion of its locking movement.

Operation

To facilitate the description of the mode of operation and the sequence of the action, the buttons 7 have been lettered *a*, *b*, *c*, *d*, *e*, and *f*, and the corresponding levers 26 have been designated *a'*, *b'*, *c'*, *d'*, *e'* and *f'*.

Assuming that the mechanism is in its locked position with both the main bolt and the auxiliary bolt projected into their operative positions:

To unlock the mechanism with the combination illustrated in the drawings, the button *f* is first depressed, to engage its lever *f'* with the pin 23 indicated by the character *f''*. This moves the plate 13 and the main bolt a short distance from its fully projected position.

The retraction of the plate is continued by the depression of the button *b* to engage its lever *b'* with the pin 23 indicated by the character *b''*. It is to be noted, however, that during the transition from one button to the other, it is essential that the first button must be held in until the next one has been actuated.

45 The buttons are then depressed in the following sequence, *e*, *c*, *d*, *b*, *a* and *c*. At this point, the plate 13 is fully retracted, permitting the lever 35 to be swung into its operative holding position by actuation of the knob 6. The latch 48 is also in its operative position ready to hold the bolt in its intermediate position if released by withdrawal of the lever 35.

55 Complete release of the main bolt, after withdrawal of the lever 35, as already defined, is effected by merely depressing the button 59 which disengages the latch 48.

65 Return of the plate and main bolt to its fully retracted position from the intermediate location at which it is held by the latch, requires only the depression of the buttons *a* and *c* and the rotation of the knob 6 to re-engage the lever 35 in the plate recess.

75 From the foregoing description taken in connection with the accompanying drawings, it will be readily apparent to those skilled in the art to which this invention appertains, that this invention affords novel and effective means for locking doors of all types and particularly the doors of safes, which, because of its peculiar construction and the fact that all of the buttons must be actuated, is practically incapable of being "picked". It is also evident that the device is inexpensive to manufacture and that changing or re-setting of its combination when desired can be quickly and easily effected.

What I claim as my invention is:

1. In a lock of the character described, a slidably mounted lock bolt, a flat plate member connected with the lock bolt to be slidable therewith and having a plurality of stops, a plurality of push buttons, and means actuated by the push buttons and operable on the stops to impart predetermined sliding movement to said flat plate member and the lock bolt connected therewith upon actuation of the push buttons in proper sequence. 80

15 2. In a lock of the character described, a slidably mounted lock bolt, and permutation means to slide the lock bolt in one direction comprising, a plurality of push buttons, a flat plate member connected with the bolt to be slidable therewith, a plurality of abutments on said plate member, and means operable by the push buttons and engageable with the abutments to transmit motion from the push buttons to the plate member and consequently the lock bolt, said abutments being so arranged on the plate member with respect to the means operable by the push buttons as to require the successive actuation of the push buttons in a proper sequence to effect the desired movement of the lock bolt. 90

20 3. In a lock of the character described, a locking member having a plurality of abutments, pivoted levers mounted for engagement with the abutments, and push buttons to actuate said levers into engagement with the abutments, and to move the locking member thereby, said abutments being so arranged with respect to the pivoted levers as to necessitate successive actuation of the push buttons in a proper sequence to effect the desired movement of the locking member. 100

25 4. In a lock of the character described, a longitudinally slidably mounted lock bolt, spring urged to an operative projected position, a member connected with the lock bolt to move directly therewith, stops mounted on said member, a plurality of push buttons, means operable by the push buttons and engageable with the stops to retract said member and the lock bolt connected therewith step by step against the action of its urging spring, the stops being so arranged on said member with respect to the push button actuated means as to require actuation of the push buttons in a proper sequence and the retention of a precedingly actuated push button in its operative position until the next successively actuated push button is depressed. 115

30 5. In a lock of the character described, a lock bolt, means yieldingly projecting the lock bolt to its operative position, means to retract the lock bolt comprising, a plate member connected with the lock bolt, a plurality of stop pins on the plate member, a plurality of pivoted levers mounted adjacent the plate member for engagement with the stop pins, and a plurality of push buttons to actuate the pivoted levers into engagement with the stop pins, said stop pins being so arranged on the plate member with respect to the pivoted levers that successive depression of the push buttons in a predetermined sequence moves the plate member step by step to retract the lock bolt. 130

35 6. In a lock of the character described, a member to be moved, and permutation means to move said member comprising, a plurality of stops connected with said member and arranged in straight rows, a lever in line with each row of stops, said levers being pivoted to turn about fixed axes to be engageable with the stops, and push buttons to actuate the levers. 145

40 7. In a lock of the character described, a mem- 150

- ber to be moved, means yieldingly urging said member in one direction, permutation means to move the member in the opposite direction comprising, a plurality of spaced stops carried by said member, a plurality of levers, means pivotally mounting said levers in alignment with the stops whereby the levers engage the stops upon being swung about their pivotal mountings, and push buttons to swing the levers about their mountings.
8. In a lock of the character described, a lock bolt yieldingly projected to locking position, permutation means for retracting the lock bolt comprising, a plurality of push buttons, means to impart movement from the push buttons to the lock bolt, said means being so arranged as to require the successive actuation of the push buttons in a predetermined sequence to effect complete retraction of the lock bolt, means engageable with the lock bolt to releasably secure the same in fully retracted position, an auxiliary lock bolt, and a connection between said auxiliary lock bolt and said securing means whereby movement of said securing means shifts the auxiliary lock bolt.
9. In a lock of the character described, a lock bolt, a plate connected with said lock bolt, a plurality of stops carried by said plate, a plurality of pivoted levers mounted for operative engagement with the stops to successively move the plate and consequently the lock bolt in one direction, push buttons to actuate said pivoted levers, and lever means having a part engageable with said plate when the plate is in its position at which the lock bolt is fully retracted to hold the plate and lock bolt in said retracted position.
10. In a lock of the character described, a main lock bolt yieldingly projected to its locking position, a plate connected with the lock bolt and movable therewith, stops carried by the plate, pivoted levers mounted for engagement with the stops and operative upon proper actuation to successively move the plate and retract the lock bolt, push buttons to actuate said pivoted levers, holding means having a part movable into a recess in said plate when the same is in its position at which the main lock bolt is fully retracted to hold the plate and main lock bolt in its retracted position, and an auxiliary lock bolt operable by the holding means.
11. In a lock of the character described, a lock bolt having a predetermined range of movement from locked to fully unlocked position, permutation means including a plurality of push buttons to retract the lock bolt to its fully unlocked position, holding means to secure the lock bolt in said fully unlocked position, and secondary holding means operable to releasably retain the lock bolt in an intermediate position.
12. In a lock of the character described, a lock bolt movable to and from locked position, means yieldingly projecting the lock bolt to its locked position, permutation means including a plurality of push buttons, means to impart movement from the push buttons to the lock bolt to retract the lock bolt, holding means to releasably secure the lock bolt in its fully retracted position, secondary holding means operable to releasably secure the lock bolt in an intermediate position, and push button actuated means to release said secondary holding means.
13. In a lock device of the character described, a lock bolt movable to and from locked position and yieldingly projected to said locked position, a plate connected with the lock bolt, a plurality

of stops on said plate, a plurality of push buttons, means operable by the push buttons and engageable with the stops to shift the plate and retract the lock bolt, and holding means engageable with one of the stops to releasably hold the plate and consequently the lock bolt in a predetermined position.

14. In a lock device of the character described, a lock bolt movable to and from locked position and yieldingly projected to said locked position, a plate connected with the lock bolt, a plurality of stops on said plate, a plurality of push buttons, means operable by the push buttons and engageable with the stops to shift the plate and retract the lock bolt, and holding means automatically engageable with one of the stops to hold the plate and consequently the lock bolt in a predetermined position.

15. In a lock device of the character described, a lock bolt movable to and from locked position and yieldingly projected to said locked position, a plate connected with the lock bolt, a plurality of stops on said plate, a plurality of push buttons, means operable by the push buttons and engageable with the stops to shift the plate and retract the lock bolt, holding means automatically engageable with one of the stops to hold the plate and consequently the lock bolt in a predetermined position, and means to disengage said holding means from the stop to free the plate and lock bolt for projection to locked position.

16. In a lock of the character described, a lock bolt, means to yieldingly project the lock bolt to operative position, a member connected with the lock bolt, a plurality of stops on said member, push buttons, means to transmit motion of the push buttons to said member through the medium of the stops whereby, upon actuation of the push buttons in a predetermined sequence, retraction of the lock bolt is effected, a latch member to releasably hold the lock bolt in a predetermined position, said latch member having a part movable into alignment with one of the stops and another part engageable by another stop to effect movement of the latch member to position its first mentioned part in alignment with said stop.

17. In a lock device of the character described, a member to be moved, spaced groups of stops on said member, a plurality of levers adjacent each group of stops, common means to pivotally mount the levers of each group with each lever arranged for engagement with at least one stop upon swinging movement thereof about its pivotal mounting, and a plurality of push buttons one engageable with each lever to swing the same into engagement with a stop and through the lever impact movement to said member.

18. In a lock device of the character described, a member to be moved, spaced groups of stops on said member, a plurality of levers adjacent each group of stops, common means to pivotally mount the levers of each group with each lever arranged for engagement with at least one stop upon swinging movement thereof about its pivotal mounting, a plurality of push buttons, one of said push buttons being engageable with each lever to swing the same into engagement with a stop and through the lever impact movement to said member, and spring means to hold the levers disengaged from the stops and to project the push buttons outwardly.

19. In a lock device of the character described including a lock bolt movable to and from operative position, a plate connected with the lock bolt and movable therewith, a plurality of spaced

stops projecting from one face of said plate, a shaft substantially parallel to said face of the plate and disposed at a distance therefrom, a plurality of levers pivotally mounted on said shaft and movable into engagement with said stops, and push buttons operable to actuate said levers.

20. In combination with a longitudinal shiftable lock bolt movable behind and in a plane parallel to the outer face of a wall, lock mechanism mounted behind the wall to retract said bolt comprising a shiftable plate connected with the lock bolt and substantially parallel with said outer face of the wall and spaced therefrom, a plurality of stops on said plate and facing the outer face of the wall, motion transmitting means between said shiftable plate and the wall, said motion transmitting means being cooperable with the stops to move the plate, and push buttons projecting through said wall and from said outer face of the wall to actuate said motion transmitting means.

21. In a lock of the character described, a wall, a shiftable lock bolt actuating member spaced from the wall, a plurality of push buttons on said wall and projectable toward the lock bolt actuating member, motion transmitting elements

mounted between said walls and said lock bolt actuating member and operable by the push buttons, and means providing a unidirectional connection between said motion transmitting elements and the lock bolt actuating member, said last mentioned means being so related to the motion transmitting elements that actuation of the push buttons in a predetermined sequence is required to effect the desired movement on the part of the lock bolt actuating member.

22. In a lock of the character described, a wall, a lock bolt actuating member movably mounted behind the wall, spaced groups of motion transmitting elements disposed between the wall and said lock bolt actuating member, means to provide a uni-directional connection between said motion transmitting elements and said lock bolt actuating member, and spaced sets of push buttons projectable through the wall to actuate the motion transmitting elements, said means affording the uni-directional connection being so related to the motion transmitting elements that the desired movement of the lock bolt actuating member requires alternate actuation of the push buttons of the spaced sets in a proper sequence.
